MAGAZINE CIGARETTE CASE WITH
CIGARETTE LIGHTING MEANS

Gustav Rikard Johnsson, Stockholm, Sweden

Application November 7, 1947, Serial No. 784,587

In Sweden November 9, 1946

3 Claims. (Cl. 312—86)

1

The present invention concerns a magazine cigarette case with automatic cigarette lighting means, the construction being so devised that, after a cigarette having been discharged from the magazine, the same is brought into a vertical position by means of a device situated exteriorly of the magazine case, whereupon the cigarette falls by its own weight on to an electric spiral filament which is mounted in a socket the length of which is substantially less than that of the cigarette. After the cigarette having been lit by said filament it may be withdrawn from said socket in a condition for immediate smoking without any additional manipulation for its lighting.

The invention is principally intended to be used in cars, in view of the fact that car drivers should avoid to take their eyes away from the road. If a magazine cigarette case according to the invention is mounted within the driver's range it will only be necessary for him to stretch his hand out and operate the magazine cigarette case being for this purpose provided with suitable actuating means.

The magazine cigarette case according to the present invention is thus generically characterized by a cigarette magazine from which one cigarette at a time can be discharged by manually operable means and then be brought into contact with a spiral filament through which an electric current is automatically closed by means cooperating with said discharge means during the discharging of said cigarette.

The invention will now be described more in detail in conjunction with the accompanying drawing of an illustrative embodiment thereof.

In the drawing,

Fig. 1 is a sectional elevation of a magazine cigarette case; and

Fig. 2 is a front elevation of the same.

In the embodiment illustrated the cigarettes 2 are horizontally disposed in the magazine 1 which in its bottom portion presents a discharge opening for the cigarettes. Projecting from this discharge opening is a discharge arrangement comprising a chute 3 secured to a spindle 4 extending along said discharge opening and journaled in the opposite side walls of the magazine case. Within the magazine case a leaf spring 5 is secured by welding or soldering, the free end of said spring being adapted to cooperate with the back edge portion of the chute 3 projecting into the magazine, as is shown in Fig. 1. The cigarettes 2 contained in the magazine are supported on the free portion of the

2

leaf spring. The back edge portion of chute 3, the leaf spring 5 and the front wall of the case 1 thus form a passage leading to the discharge opening, said passage being only sufficiently wide to pass one single cigarette on to the bottom of said chute 3 when the discharge arrangement is in its unoperated position indicated in full lines in Fig. 1, the downward extension of spring 5 being so adjusted that the free end thereof will be at the level of the uppermost portion of said cigarette, while at the same time the spring 5 will engage the back edge portion of the chute 3 and preferably exert a certain resilient pressure thereon. In this unoperated position the discharge arrangement may be arrested by suitable stop means or the like (not shown).

The spindle 4 projects through the left hand side wall of the magazine case 1 where the spindle end is at first bent vertically upward and then horizontally outward at right angles to the main portion of the spindle and parallel to the bottom of the chute 3. A second chute or bridge 7 is pivotally mounted on the last-named spindle portion in such a manner as to be capable of being swung from a horizontal position to a vertical position, as is indicated by broken lines in Fig. 2. In its horizontal position the bridge 7 overlaps and engages the chute 3 in such a manner that the chute 3 and the bridge 7 can be swung in common in a vertical plane at right angles to the vertical plane in which the bridge 7 is capable of being swung into its vertical position about its spindle portion. For this purpose the bridge 7 is provided with a lug or extension 8 adapted to rest on the bottom of the chute 3 or in a recess therein when the bridge is in its horizontal position. Accordingly, in this position it is possible, by exerting a downwardly directed pressure on the bridge 7 intermediate its two points of support, to swing the bridge 7 and the chute 3 in common and against the action of the spring 5 from said unoperated position to the discharge position shown in broken lines in Fig. 1. In so doing the lowermost cigarette is released and will roll down to the front edge portion of the chute 3 and bridge 7, the spring 5 being at the same time tensioned by the back edge of the chute 3 and introduced beneath the penultimate cigarette, whereby the latter is prevented from slipping down into the discharge opening.

Upon removing the pressure from the bridge 7 the spring 5 will return the chute 3 and bridge 7 to the unoperated position, and the discharged

cigarette will remain in the chute and bridge outside the magazine case, the lowermost cigarette in the magazine at the same time slipping down into its discharge position. An upwardly directed pressure is then exerted on the bridge 7 between said points of support, whereupon the bridge is released from the chute 3 and can be swung about its axis 9 into a vertical position. The cigarette lying on the bridge 7 will partake in this movement, and towards the end thereof the cigarette will slide downward by its own weight until eventually it will contact a spiral filament 6 provided in a socket which is constituted by an extension 10 of the bridge. When the bridge is being swung towards its vertical position it may be caused to close a pair of contacts diagrammatically illustrated at 11 through which current is fed to the filament from the source of current 12. In a few seconds the cigarette will have been lit by the filament and may then be conveniently withdrawn from the socket. The bridge is then swung back again into its horizontal position, and during this movement it opens said contacts, whereby the current supply to the filament will cease.

As the chute 3 is released and is arrested in its unoperated position a vibration will occur in the spring 5 which agitates the cigarettes disposed in the magazine, whereby the cigarettes will not tend to be squeezed together or against the boundary walls.

The invention, of course, is not limited to the embodiment illustrated and described herein, and nor to the application in conjunction with cars, the same being capable of various modifications and applications without departing from the spirit of the invention as defined in the following claims.

What I claim is:

1. A magazine cigarette case comprising a cigarette magazine for horizontally disposed cigarettes, a discharge opening in the bottom portion of said case, automatically operated electric cigarette lighting means, manually operable means for discharging one cigarette at a time from said magazine and for bringing said cigarette into contact with said lighter, said discharge means comprising a spring-actuated chute pivotally mounted along said discharge opening, and a pivotally mounted bridge co-operating with said chute and forming a releasable continuation thereof, said chute being secured to a spindle journaled in the side walls of said case, said spindle having one end thereof extending outside one of said case walls, said spindle end comprising a portion at right angles to the main portion of the spindle and extending parallel to the bottom of said chute, said bridge being pivoted on said last-named spindle end portion.

2. A magazine cigarette case comprising a cigarette magazine for horizontally disposed cigarettes, a discharge opening in the bottom portion of said case, automatically operated electric cigarette lighting means, manually operable means for discharging one cigarette at a time from said magazine and for bringing said cigarette into contact with said lighting means, said

discharge means comprising a spring-actuated chute pivotally mounted along said discharge opening, a pivotally mounted bridge forming a continuation of said chute, said chute being secured to a spindle journaled in the side walls of said case, said spindle having one end thereof extending outside one of said case walls, said spindle end comprising a portion at right angles to the main portion of the spindle and extending parallel to the bottom of said chute, said bridge being pivoted on said last-named spindle end portion, engagement means provided on said bridge and releasably co-operating with said chute in such a manner that said bridge, when subjected to a downward pressure intermediate its points of support, will cause said chute to be swung from its unoperated position to its discharge position, and that said bridge, when subjected to an upwardly directed pressure between said points of support, will be disengaged from said chute and itself rotated about its axis into a vertical position said bridge when moving into a vertical position energizing said lighting means.

3. A magazine cigarette case comprising a cigarette magazine for horizontally disposed cigarettes, a discharge opening in the bottom portion of said case, said discharge means comprising a spring-actuated chute pivotally mounted along said discharge opening, a pivotally mounted bridge co-operating with said chute and forming a releasable continuation thereof, said chute being secured to a spindle journaled in the side walls of said case, said spindle having one end thereof extending outside one of said case walls, said spindle end comprising a portion at right angles to the main portion of the spindle and extending parallel to the bottom of said chute, said bridge being pivoted on said last-named spindle end portion, said chute and bridge serving in common to receive a cigarette being discharged and said bridge further serving to move said cigarette into a vertical position, a socket forming an extension of said bridge, the length of said socket being substantially less than that of the cigarette, a spiral filament disposed in the outer end of said socket, a source of current, circuit means between said source and said filament and contact means in said circuit for opening and closing the circuit through said filament, said contact means being actuatable by said bridge to closed position when said bridge is swung towards its vertical position and to be opened when the bridge is being swung back to its horizontal position.
